UNITED STATES PATENT OFFICE.

FRANÇOIS BAVEREY, OF OULLINS, FRANCE, ASSIGNOR TO SOCIETE DU CARBURATEUR ZENITH, A CORPORATION OF FRANCE.

CARBURETER.

1,186,371.

Specification of Letters Patent.

Patented June 6, 1916.

Application filed July 30, 1914. Serial No. 854,105.

To all whom it may concern:

Be it known that I, FRANÇOIS BAVEREY, a citizen of the Republic of France, residing at Oullins, France, Rue Pasteur 36, have invented a new and useful Improvement in Carbureters, of which the following is a full, clear, and exact description, reference being had to the accompanying drawings, forming part of this specification, in which—

10 Figure 1 is a vertical section showing one form of my improved carbureter; Fig. 2 is a cross section on the line II—II of Fig. 1; and Fig. 3 is a view similar to Fig. 2, showing the piston in a different position. Fig. 4 is a longitudinal view showing the device in connection with the float chamber of a carbureter.

15 My invention relates to sunken jet types of carbureters, which jet may be used either alone or in conjunction with another jet.

The invention also relates to a special jet for slow speed running in the preferred form.

20 The object of the invention is to aid in starting the engine by increasing the quantity of gasoline fed by the sunken jet.

In the preferred form, it also provides for increasing the gasoline fed by the special slow speed jet.

25 30 In carrying out these objects, I partly or entirely close the air entrance or air inlet for the sunken jet; and where the special slow speed jet is used, by partly or wholly closing its air inlet.

35 In the drawings, I have shown a preferred form of my invention, 2 representing an atmospheric chamber or well, having in its upper portion a sidewise extending tube 3, opening thereinto. The sunken jet 4 is at 40 the bottom of this well 2, and is open to the atmosphere through the holes 5 in the tube 3. These holes may be large enough to give atmospheric pressure in the well, if desired, or the holes may be smaller if the 45 sunken jet is to be fed by the suction in normal running. The lower end of the sunken jet 4 is in communication with the float chamber 11 by means of the passage 12, which passage is also in communication with the main jet 13 by means of a passage 15, and 16 is a passage communicating with the annular fuel outlet or compensating nozzle 17 and the lower portion of the well 2.

Within the tube 3 is a piston or plunger 55 6 having an actuating member 7, projecting

outwardly through the slot in the wall of the tube. This member 7 may have a connection to the dash or driver's seat or any convenient place for operating the plunger. This plunger is normally held in its rearward position, with the attachment 7 against the back end of the slot, by a spiral spring 8, and when in its open normal running position, the vent holes 5 are open to the atmosphere. When the plunger is moved 60 to its inner position by the driver, the vent holes 5 are closed and a small hole 9, entering a central cavity in the plunger is opened through one of these vents, as shown in Fig. 2. This small hole is so placed as to allow 65 entrance of air in smaller amounts to the well 2, and the adjustable slow speed jet 10. On account of this hole 9 being smaller than the annular space around the slow speed jet, and the openings 14 the suction 70 is increased around the nozzle of the jet 10, thus enriching the mixture furnished by the slow speed jet. The operation, therefore, is as follows:—When running under normal 75 conditions the plunger 6 is in the position shown in Fig. 3 and air is admitted to the well 2 through the comparatively large opening 5; when the carbureter is in this condition and if the throttle is sufficiently near 80 its closed position to allow the slow speed jet 10 to operate, in the well known manner, the maximum amount of air will be allowed to sweep past the nozzle of jet 10, but if the plunger 6 is shifted to the position shown 85 in Fig. 2, then the amount of air admitted 90 to the well is materially reduced. The obvious result will be an enrichment of the mixture furnished. If, however, the throttle be opened so as to allow jet 4 to operate through the "compensating nozzle", in the well known manner, described in the patent 95 to Baveray No. 907,953, then the shifting of the plunger from the position of Fig. 3 to the position of Fig. 2 will also result in 100 an enrichment of the mixture by decreasing the amount of air admitted along with the fuel to the "compensating nozzle".

Changes may be made in the number of jets, the means for varying the suction, etc., without departing from my invention.

105 I claim:

1. In a carbureter, a constant level fuel chamber, a well having an air inlet in its upper portion, a fuel channel extending from the constant level chamber into the 110

well, a feed channel leading from the lower portion of the well into the carbureting passage, a slow speed jet in the well communicating with the carbureting passage, and a hand controlled valve device arranged to control the admission of air to the well to vary the richness of the mixture fed by the slow speed jet; substantially as described.

2. In a carburetor, a constant level fuel chamber, a well having an air inlet in its upper portion, a fuel supply channel extending from the constant level chamber into the well, a slow speed jet in said well arranged to feed mixture to the carbureting chamber, other means for feeding mixture to the carbureting chamber, and a hand controlled valve device arranged to control the admission of air to the upper portion of the well to vary the richness of the mixture fed by the slow speed jet to the carbureting chamber; substantially as described.

3. In a carburetor, a constant level fuel chamber, a well having an air inlet in its upper portion, a fuel supply channel extending from the constant level chamber into the well, a slow speed jet in said well communicating with the carbureting chamber, a valve for controlling the admission of air to said well comprising a casing having openings therethrough, and a plunger arranged to cut off said opening, said plunger having a smaller opening therethrough arranged to register with the opening through the wall of the valve casing; substantially as described. 35

In testimony whereof, I have hereunto set my hand.

FRANCOIS BAVIEREY.

Witnesses:

GASTON JEANIAUX,
MARIUS MERBLAZ.
